UNITED STATES PATENT OFFICE

MATSON C. TERRY, OF MANSFIELD, OHIO, ASSIGNOR TO WESTINGHOUSE ELECTRIC & MANUFACTURING COMPANY, A CORPORATION OF PENNSYLVANIA

REFRIGERATOR EQUALIZER VALVE

Application filed September 28, 1927. Serial No. 222,598.

My invention relates to refrigerating systems of the compression type and particularly to devices for automatically relieving the compressor of load during periods of starting in order that the starting torque required may be lessened, and it has for an object to provide apparatus of the character designated which shall operate automatically and reliably without care or attention for an indefinite period of time. It has for a further object to provide apparatus of this character which shall be capable of effecting direct and open communication between the high and low pressure portions of the refrigerating system at times of starting in order that the suction and discharge pressures of the compressor may be substantially equalized and which apparatus shall, at all other times, maintain a fluid-tight seal between the two portions in order that the effectiveness of the compressor may not in any way be affected.

These and other objects, which will be made apparent throughout the further description of my invention, may be attained by the employment of the apparatus herein-after described and illustrated in the accompanying drawing in which:

Fig. 1 is a diagrammatic representation of a conventional compression refrigerating system having applied thereto one form of unloading device arranged in accordance with my invention; and,

Fig. 2 is a partial diagrammatic representation of another form of unloading device which is similar to that shown in Fig. 1 with the exception that the magnetic unloader and the motor starting winding are arranged in series instead of in parallel.

It is generally recognized that, at present, the 110 volt electric light circuit provided in the average household is adapted for supplying energy to only those electric appliances which never require in excess of 15 amperes current draw. It is, therefore, desirable that refrigerating machines of the domestic or household type come within this requirement, but it has been found that in refrigerating machines of the enclosed type, that is, refrigerating machines in which both

the compressor and the motor are enclosed in a single, fluid-tight, hermetically sealed casing and in which motors of the split-phase type are generally employed, that the current draw of both starting and running windings during times of starting for conventional motors of greater capacity than $\frac{1}{3}$ H. P. may materially exceed 15 amperes. With conventional motors of greater than $\frac{1}{3}$ H. P. the conditions are especially severe when the current supply fails only momentarily, that is, for only a few seconds, at which time the compressor must start against full load because of the fact that the shut-off period has not been sufficiently long to permit any material equalization of pressures between the suction and discharge sides of the compressor or between the high and low pressure portions of the system. It is apparent that, at times such as these, the compressor is compelled to work up to normal operating speed against full load and consequently the current draw of the motor is excessive.

It has heretofore been proposed to provide a valved conduit between the high and low pressure portions of the system which is closed during normal operation and which is open only during the starting periods. Such valved conduits have been controlled by some mechanical means, such as a governor, which is responsive to the speed of the motor or the compressor shaft. However, apparatus of this character must necessarily be mechanically and operatively connected to the rotating element or elements so that certain structural limitations are imposed which may seriously interfere with obtaining the most compact form of arrangement. Furthermore, mechanical controlling means of the governor type tend to destroy the static and dynamic balance of the rotating element, which obviously is very objectionable.

I have, therefore, conceived of actuating the equalizing valve by means of an electromagnet or solenoid, and of utilizing the initial surge of current incidentally created in starting to temporarily energize the solenoid and hold the valve open until such time as

the compressor reaches its normal operating speed. In other words, the compressor is incapable of building up any pressure difference between the suction and discharge sides until such time as it has attained its normal operating speed, at which time the torque of the motor is sufficient to carry full load, the current draw drops to normal and the equalizing valve closes. I have found such an arrangement to be extremely reliable in that it utilizes, as an actuating force, electric energy which must always be available in order for the motor to start. At the same time, the arrangement possesses far greater flexibility in that the valve, together with its actuating mechanism, may be located with no relation whatsoever to the moving parts and hence certain structural limitations are avoided.

Referring to the drawing for a more detailed description of my invention, I show in Fig. 1, a compressor 10 which is of the reciprocating type although it is to be understood that my invention is also applicable to other forms of compression mechanisms. The compressor 10 discharges through a conduit 11 to a condenser 12, the refrigerant condensate formed therein being conveyed by means of a conduit 13 to an evaporator or cooling element 14. An expansion valve 15 is interposed between the condenser 12 and the evaporator 14 and operates to control the flow of liquid refrigerant to the latter in a manner well understood in the art. Refrigerant vapor generated in the evaporator 14 is returned through a conduit 16 to the inlet of the compressor 10. The foregoing description refers merely to a diagrammatic illustration of the conventional form of compression refrigerating system and it may be said that the discharge portion of the compressor 10 together with the conduit 11, condenser 12 and conduit 13 constitute the high pressure portion of the system, while the conduit 16, evaporator 14 and the intake portion of the compressor 10 constitute the low pressure portion of the system. A check valve 17 is preferably provided in the conduit 16 for resisting back leakage or return flow of the high pressure refrigerant fluid to the low pressure portion of the system at any time.

The compressor 10 is driven by an electric motor which may be of the split-phase type embodying starting and running windings 21 and 22 respectively. One side of both windings is connected by a common lead 23 to one leg of a power main represented at 24, while the other sides of both windings are connected through respective leads 25 and 26 to the other leg of the power main 24. Located in the lead 23 is a master controlling switch 27 which is actuated automatically in response to the conditions prevailing within the refrigerating system. In other words, this switch operates automatically to start and

stop the refrigerating system in order to maintain predetermined temperatures in the refrigerator box, all as is well understood in the art.

Connected in series with the starting winding 21 and the lead 25 is the starting winding switch 28. While various forms of switches may be employed, I have shown, for purposes of illustration, a switch composed of transparent glass casing 29 preferably formed in the manner illustrated and containing bodies of conducting liquid, such as mercury, 31 and 32, having normal levels such as indicated at 33, 34 and 35. Terminal connections 36 and 37 are provided in the casing 29 and are connected in the lead 25 as shown. Associated with one leg of the casing 29 is a solenoid winding or coil 38 which is connected in circuit with the lead 26 of the running winding circuit, as shown. A member 39 of suitable magnetic material is provided in the casing 29 and serves as an armature member for the coil 38.

Connected in parallel with the starting winding 21 through leads 41 is a solenoid 42 which, like the starting winding, is controlled by the switch 28. The solenoid 42 is composed essentially of a coil 43 and an armature member 44. The armature member 44 is connected through operating mechanism, such as a lever 45, to a valve 46, a spring 47 being provided for normally retaining the valve in closed position, such as illustrated. The valve 46 is provided with connections 47' and 48, one of which is connected by a conduit 49 to the high pressure portion of the refrigerating system and the other connection by means of a conduit 51 to the low pressure portion of the system, the conduits 49 and 51 and the valve 46 forming, in effect, a by-pass about the compressor and a direct connection between the high and low pressure portions of the refrigerating system.

From the foregoing description, the operation of my invention will be apparent. Assuming the refrigerator to be in active use but the temperature in the refrigerator box to be below the upper control limit, the switch 27 is temporarily open and the entire system is consequently de-energized. The starting winding switch 28, the solenoid 42 and the valve 46 are retained in the positions illustrated. From previous operation, refrigerant fluid at relatively high pressure prevails in the compressor 10, the conduit 11 and the condenser 12, and is prevented from escaping into the remainder or low pressure portion of the system by the check valve 17. It is obvious, that by preventing the escape of high pressure and high temperature refrigerant into the low pressure and low temperature portion of the system during the various inactive periods, serious thermo-dynamic losses are avoided.

However, upon the temperature in the re-

frigerator rising sufficiently, the switch 27 automatically closes to energize the running winding 22 of the motor. At such times, there is an initial surge of current (assuming, for example, $\frac{1}{8}$ H. P. motor and current of 110 volts, 60 cycles) of approximately 8 amperes, this current being capable of energizing the solenoid winding 38 of the starting winding switch 28 sufficiently to draw the armature core downwardly and cause the conducting fluid in the casing 29 to assume the level indicated at 52 and thus complete the circuit between the terminals 36 and 37. In other words, at such times, the starting winding 21 is connected through the lead 25 to the power main 24.

The closing of the switch 28 also connects the solenoid 42 in circuit with the power main, drawing the armature core 44 downwardly and thus opening the valve 46. Opening of the valve 46 provides direct communication between the high and low pressure portions of the system and hence the pressures are substantially equalized therebetween and the compressor 10 is incapable of building up any pressure difference as long as the valve 46 is open.

Upon the motor reaching its normal operating speed, the current draw drops to normal, for example, from 8 amperes to $2\frac{1}{2}$ amperes and, the latter amount of current being insufficient to energize the coil 38 sufficiently to retain the core 39 in its down position, the latter rises to the position illustrated and the conducting fluid within the casing 29 separates into two bodies, breaking the circuit of the starting winding 21 and of the solenoid 42. At this time the spring 47 acts to draw the solenoid core 44 upwardly and to close the valve 46. Thereafter, the compressor is free to develop a pressure difference between the high and low pressure portions of the refrigerating system in a manner well understood in the art. The starting winding switch 28, the solenoid 42 and the valve 46 remain in the same positions until such time as the master control switch 27 has opened to stop the operation and until it again closes to restart the operation, whereupon the starting winding 21 is temporarily energized and the valve 46 is again temporarily opened in the manner heretofore described.

Although it will be apparent from the foregoing description of operation that rather severe conditions are imposed upon the compressor and motor in normal starting, nevertheless, the conditions prevailing are even more severe when the current in the power main fails temporarily.

As stated heretofore, the machine normally operates intermittently, that is, a period of operation of one or more hours is usually followed by an inactive period of one or more hours. The machine, therefore, re-

mains inactive for a substantial period and even though the check valve 17 is provided, there is some reduction in the pressure difference prevailing between the high and low pressure portions of the system. This is caused by the fact that leakage of some refrigerant fluid through both the compressor and the check valve is unavoidable. However, when the machine is operating and the current in the main fails for a period of, for example, ten seconds or less, the inactive period is so short that, at time of starting, that is, when the current supply returns to the main 24, the pressure difference is almost exactly that prevailing during normal operation. In other words, the inactive period has been of insufficient duration to effect any noticeable reduction in pressure difference between the high and low portions. At times, such as these, my pressure equalizing device is especially valuable for preventing excessive current draw and for insuring proper starting of the refrigerating machine.

Referring now to Fig. 2, I show a form of control system which is similar to that shown in Fig. 1, with the exception that the electromagnetic means for actuating the pressure-equalizing valve is arranged in series with the motor starting winding instead of in parallel. In this arrangement, the motor starting winding 21 is connected through a lead 61 to the coil 43 of the solenoid 42 and through a lead 62 to the terminal connection 36 of the switch 28. The other terminal connection 37 of the switch 28 is then connected through a lead 63 to a leg of the power main 24, as illustrated.

It will be apparent from the foregoing description that the motor starting winding 21, the solenoid 42 and the switch 28 are all arranged in series so that the latter controls the flow of current through the circuit thus formed. Operating results are thus procured similar to those obtained with the system illustrated in Fig. 1.

It will be apparent from the foregoing description, that, by means of the foregoing arrangement, overloading of the motor and the passage of abnormal current flow is positively prevented, the load on the motor being almost entirely removed until such time as it attains its normal operating speed. It will be further apparent that, by means of my invention, both the reliability of operation as well as the commercial application of refrigerating machines of the household type are very materially improved.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are im-

posed by the prior art, or as are specifically set forth in the appended claims.

What I claim is:

1. In combination with a refrigerator system embodying a low-pressure portion including an evaporator, a high-pressure portion including a condenser, a compressor for circulating refrigerant fluid from the low-pressure portion to the high-pressure portion, a motor for driving the compressor, and means for supplying electrical energy to the motor, of means for equalizing the pressure difference between the high and low pressure portions of the system, and means responsive to the initial surge of current through the motor for rendering said equalizing means effective.
2. In combination with a refrigerator system embodying a low-pressure portion including an evaporator, a high-pressure portion including a condenser, a compressor for circulating refrigerant fluid from the low-pressure portion to the high-pressure portion, a motor for driving the compressor, and means for supplying electrical energy to the motor, of communicating means directly connecting the high and low-pressure portions of the refrigerating system, means for opening and closing said connecting means, and means responsive to the initial electrical energy surge through the system for actuating said opening and closing means to open position.
3. In combination with a refrigerator system embodying a low-pressure portion including an evaporator, a high-pressure portion including a condenser, a compressor for circulating refrigerant fluid from the low-pressure portion to the high-pressure portion, a motor for driving the compressor, and means for supplying electrical energy to the motor, of a means for by-passing the compressor and providing direct communication between the high and low-pressure portions of the system, said means including a valve, electro-magnetic means for actuating the valve to open position, and means responsive to the initial electrical energy surge through the system for energizing said electro-magnetic means.
4. In combination with a refrigerating system embodying a low-pressure portion including an evaporator, a high-pressure portion including a condenser, a compressor for circulating refrigerant fluid from the low-pressure portion to the high-pressure portion, a motor for driving the compressor, and means for connecting the motor in circuit with a source of electrical energy, of a master switch for controlling the flow of electrical energy to the motor, a normally closed valved passage for by-passing the compressor and for directly connecting the high and low-pressure portions of the system, and electro-magnetic means effective

upon the abnormal flow of current incident to starting of the motor for opening said valve.

5. In combination with a refrigerating system embodying a low-pressure portion including an evaporator, a high-pressure portion including a condenser, a compressor for circulating refrigerant fluid from the low-pressure portion to the high pressure portion, a motor for driving the compressor, and means for connecting the motor in circuit with a source of electrical energy, of a passage by-passing the compressor and connecting the high and low-pressure portions of the system, a master switch for controlling the flow of electrical energy from the source to the system, and electro-magnetic means rendered effective by the initial surge of current through the motor for temporarily opening said valve.

6. In combination with a refrigerating system embodying a low-pressure portion including an evaporator, a high-pressure portion including a condenser, a compressor for circulating refrigerant fluid from the low-pressure portion to the high pressure portion, a motor for driving the compressor, said motor embodying starting and running windings, and means for connecting the motor to a source of electrical energy, of a master switch for controlling the flow of electrical energy from the source to the system, a switch for controlling the flow of electrical energy through the starting winding, means normally ineffective for equalizing the pressure between the high and low-pressure portions of the system, means for actuating said pressure-equalizing means, and means responsive to abnormal flow of current incident to starting of the motor for temporarily closing the starting winding switch and for temporarily rendering said pressure-equalizing means effective.

7. In combination with a refrigerating system embodying a low-pressure portion including an evaporator, a high-pressure portion including a condenser, a compressor for circulating refrigerant fluid from the low-pressure portion to the high-pressure portion, a motor embodying running and starting windings for driving the compressor, and means for connecting the motor in circuit with a source of electrical energy, of a master switch for controlling the flow of electrical energy from the source to the system, a switch for controlling the flow of electrical energy through the starting winding, pressure-equalizing means normally ineffective connecting the high and low-pressure portions of the system, and electro-magnetic means for actuating both the starting winding switch and for rendering the pressure equalizing means effective upon temporary abnormal flow of current created by the starting of the motor.

8. In combination with a refrigerating system embodying a low-pressure portion including an evaporator, a high-pressure portion including a condenser, a compressor for circulating refrigerant fluid from the low-pressure portion to the high-pressure portion, a motor embodying running and starting windings for driving the compressor, and means for connecting the motor in circuit with a source of electrical energy, of a master switch for controlling the flow of electrical energy from the source to the system, a switch for controlling the flow of electric energy through the starting winding circuit, electro-magnetic means for actuating the starting winding switch, pressure equalizing means normally ineffective for connecting the high and low-pressure portions of the system, and electro-magnetic means for actuating said pressure-equalizing means to render the same effective, both said first and second electro-magnetic means being adapted to be energized by the abnormal flow of current to the system created during the motor starting periods.

9. In combination with a refrigerating system embodying a low-pressure portion including an evaporator, a high-pressure portion including a condenser, a compressor for circulating refrigerant fluid from the low-pressure portion to the high-pressure portion, a motor embodying running and starting windings for driving the compressor, and means for connecting the motor in circuit with a source of electrical energy, of a master switch for controlling the flow of electrical energy from the source to the system, a switch for controlling the flow of electric energy through the starting winding, electro-magnetic means connected in circuit with the running winding for actuating the starting winding switch, means normally ineffective for equalizing the pressures between the high and low-pressure portions of the system, and electro-magnetic means connected in circuit with the starting winding for rendering said pressure equalizing means effective, both said first and second electro-magnetic means being adapted to be energized by the abnormal flow of electrical energy created during starting periods of the motor.

10. In combination with a refrigerating system embodying a low-pressure portion including an evaporator, high-pressure portion including a condenser, a compressor for circulating refrigerant fluid from the low-pressure portion to the high-pressure portion, a motor embodying running and starting windings for driving the compressor, and means for connecting the motor in circuit with a source of electrical energy, of a switch for controlling the flow of electrical energy through the motor starting winding, electro-magnetic means connected in circuit with the motor running winding for actuat-

ing said switch, pressure-equalizing means normally ineffective for connecting the high and low-pressure portions of the system, electro-magnetic means for actuating said pressure-equalizing means to render the same temporarily effective, and means responsive to the initial electrical energy surge through the motor for actuating said pressure equalizing means.

11. In combination with a refrigerating system embodying a low-pressure portion including an evaporator, a high-pressure portion including a condenser, a compressor for circulating refrigerant fluid from the low-pressure portion to the high-pressure portion, a motor embodying running and starting windings for driving the compressor, and means for connecting the motor in circuit with a source of electrical energy, of a switch for controlling the flow of electrical energy through the motor starting winding, electro-magnetic means responsive to the initial surge of current through the motor running winding for actuating said switch, pressure-equalizing means normally ineffective for connecting the high and low-pressure portions of the system, and electro-magnetic means connected in parallel with the motor starting winding whereby electro-magnetic means for actuating said pressure-equalizing device is controlled by the motor starting winding switch.

12. In combination with a refrigerator system embodying a low-pressure portion including an evaporator, a high-pressure portion including a condenser, a compressor for circulating refrigerant fluid from the low-pressure portion to the high-pressure portion, a motor for driving the compressor, and means for supplying electrical energy to the motor, of means for bypassing the compressor and connecting the low-pressure and high-pressure portions of the system, said means including a normally closed valve, and means responsive to the abnormal surge of motor-starting current for opening said valve.

13. In combination with a refrigerator system embodying a low-pressure portion including an evaporator, a high-pressure portion including a condenser, a compressor for circulating refrigerant fluid from the low-pressure portion to the high-pressure portion, a motor for driving the compressor, and means for supplying electrical energy to the motor, of means connecting the compressor cylinder directly to the low-pressure portion of the system, said means including a normally closed valve, and electromagnetic means responsive to the abnormal surge of motor-starting current for opening said valve.

14. In combination with a refrigerator system embodying a low-pressure portion including an evaporator, a high-pressure por-

tion including a condenser, a compressor for circulating refrigerant fluid from the low-pressure portion to the high-pressure portion, a motor for driving the compressor, and means for supplying electrical energy to the motor, of a pressure-equalizing passage connecting the compressor cylinder directly to the low-pressure portion of the system, a valve normally closing said passage, and electromagnetic means responsive to the abnormal surge of motor-starting current for opening said valve.

10 In testimony whereof I have hereunto subscribed my name this 12th day of Sept., 1927.
